MANUEL N. ROBLES

By James Rainey Jr.
Attorney.

UNITED STATES PATENT OFFICE.

MANUEL N. ROBLES, OF MEXICO, MEXICO.

STEREOSCOPE.

1,322,953.

Specification of Letters Patent. Patented Nov. 25, 1919.

Application filed March 24, 1919. Serial No. 284,583.

To all whom it may concern:

Be it known that I, MANUEL N. ROBLES, a citizen of the United Mexican States, residing at Mexico, Federal District, Mexico, 5 have invented certain new and useful Improvements in Stereoscopes, of which the following is a specification.

This invention relates to stereoscopes, and particularly to those called "taxiphotos".

10 The object is to provide an apparatus for continuously sliding stereoscopic pictures in front of eye-pieces from one rhomboidal follower box to another. The positives or pictures on plate glass stand in the follower 15 boxes on their edges, and means are provided for maintaining invariable tension on the total of pictures, whether they are piled up in one of the follower boxes or distributed in any other proportion in the two boxes, ac- 20 cording to the number of pictures which, at any given moment, has been passed before the eye-glasses. Means have also been pro- 25 vided for reversing the course of said pictures as well as for piling them up in the follower box that is being charged.

In the drawing:

Figure 1 is a top view of the apparatus.

Fig. 2, is a front view in elevation of same.

Fig. 3, is a perspective view of the picture 30 pile holder.

Now, referring to the drawings, (1) and (2) are rhomboidal follower boxes attached to or integral with the front sight box (3), the fore part (4) of which is open to let in 35 the light, while the rear (5) carries the common adjustable eye-pieces or lenses (6).

In the sight box (3) are mounted spindles (7), having chain wheels (8) connected by the link chain (9). One of the spindles is 40 geared to the handle (10) by the worm (11) and worm wheel (12), in order to be re- 45 volved and therewith the friction rubber wheels (13), which engage the pictures or plate glass (14), that is exposed in the middle part of the sight box (3), which part is one third of the sight box, or equal to the width of the follower boxes (1) and (2).

A simple presser bar (15) fulcrumed at (18), having ends (16) folded down and carrying presser casters (17), is thrown toward 50 the follower box (1) in Fig. 1, so as to produce the escapement of the plates (14) sliding from the follower box (2), when they

have just passed the middle portion of the sight box (3).

55 This presser bar (15) has a common spring attachment, not shown, to maintain it elastically against plates of the follower box momentaneously changed.

The bottoms (19) of the follower boxes (1) and (2) are grooved at (20), and a string (21), passing from a holder block (22) down into the grooves (20) around the idlers (23) in the sight box (3), is adjusted 60 tight to the other holder block (24), in order 65 to keep the plates upright in the boxes.

The operation of the apparatus is as follows:

A number of pictures are placed in the follower box (2), tightening the string (21) 70 between the holder blocks (22) and (24), then, the first pictures will abut against the friction wheel (13) opposite the follower box (2), and by turning of the handle (10) the wheel engages the plate or picture, slid- 75 ing it toward the follower box (1) into which it passes due to the pressure of the caster (17) swung to the position shown in Fig. 1. As soon as the first plate has passed the friction wheel (13) facing the follower 80 box (2), then the friction wheel (13), facing the follower box (1), engages the first plate, leaving the second plate to be engaged and carried along. This operation is repeated 85 until all the pictures have been slid to the follower box (1). In order to return the plates to the follower box (2), the end of the presser bar (15) opposite the follower box (2) is swung out, while the other end op- 90 posite the follower box (2) is turned to op- erative position, exerting pressure upon the plates or pictures when reaching the en- trance to the follower box (2), and the han- dle (10) is revolved to the contrary.

Having thus described my invention what 95 I claim is:

An apparatus for sliding stereoscopic picture plates, comprising two rhomboidal fol- 100 lower boxes adjoining a sight box spaced apart by a light opening in said sight box, equal in length to the width of one of said follower boxes, adjustable eye-pieces in said sight box between said follower boxes, a holder block for the plates in each follower box and a tension means extended between 105 said holder blocks adapted to slide through

said sight box, and interchangeable means for drawing a picture plate exposed to the sight box from the stock of plates in one follower box and passing it in front of said light opening and toward the receiver follower box, an interchangeable presser means for pushing said plates into the receiver follower box when said plate has

traveled two thirds of the length of said sight box, transferring thereby a fraction of 10 the tension length from the transmitter to the receiver follower box.

In testimony whereof I have affixed my signature.

MANUEL N. ROBLES.
